DESIGN FOR AN EMBOSSED LEATHER SHEET OR SIMILAR ARTICLE

James E. Goldberg, New York, N. Y.

Application July 13, 1938, Serial No. 78,450

Term of patent 3½ years

To all whom it may concern:

Be it known that I, James E. Goldberg, a citizen of the United States, and a resident of the city, county, and State of New York, have invented a new, original, and ornamental Design for an Embossed Leather Sheet or Similar Article, of which the following is a specification, reference being had to the accompanying drawing, forming a part thereof.

The figure of the drawing is a face view of an embossed leather sheet showing my design.

I claim:

The ornamental design for an embossed leather sheet or similar article, substantially as shown.

JAMES E. GOLDBERG.
